UNITED STATES PATENT OFFICE.

CARL A. KULENKAMPFF, OF NEW YORK, N. Y.

ICE-CREAM-STORAGE APPARATUS.

Application filed April 13, 1921. Serial No. 461,153.

To all whom it may concern:

Be it known that I, CARL A. KULENKAMPFF, a citizen of the United States, and a resident of the city of New York, borough 5 of Manhattan, in the county and State of New York, have invented a new and Improved Ice-Cream-Storage Apparatus, of which the following is a full, clear, and exact description.

10 This invention relates to storage devices for ice cream and has for an object to provide an improved construction of storage units which will permit the ready circulation of the cooling medium without interfering 15 with the insertion and removal of the filled container of ice cream.

Another object of the invention is to provide a storage apparatus for ice cream and the like in which a double walled container 20 is presented with an arrangement whereby the parts may be readily separated for repair or renewal.

In the accompanying drawing—

25 Figure 1 is a perspective view of a complete storage apparatus disclosing one embodiment of the invention.

Figure 2 is a longitudinal vertical section through Figure 1 approximately on line 2—2.

30 Figure 3 is an enlarged fragmentary longitudinal vertical sectional view through one of the double walled receptacles embodying the invention.

Referring to the accompanying drawing 35 by numerals, 1 indicates a box or large container adapted to receive a number of receptacles 2 which in turn receive the containers carrying the ice cream or other material. A filling 3 of cork or other suitable 40 material is positioned in the box 1 and packed carefully around the double walled receptacles 2. As indicated in Figures 1 and 2, a pipe 4 enters the box or container 1 and is intended to supply a cooling medium, as for instance, cool brine to the receptacles 2.

By the arrangement indicated in Figure 2, the brine enters the first receptacle 2 and passes from the bottom thereof to the top 50 and then down the connecting pipe 5 to the bottom of the next container. After the brine passes to the second receptacle it moves upwardly to another connecting pipe 5 and down to the third receptacle and so on 55 through all the receptacles used until it is finally discharged out the end pipe 6. Each

of the receptacles 2 is constructed as shown in Figure 3 from which it will be observed that each receptacle is provided with an outside casing 7 and an inner casing 8 connected at the upper end but spaced apart at all other points. A supporting ring 9 is provided and formed with an annular notch 10 in which the upper edge of the casing 7 is fitted and to which it is secured in 60 any desired manner, as for instance, by solder 11. The ring 9 is provided with an inwardly extending flange 12 whereby a gasket 13 may rest on said flange and in fact the entire upper part of the ring 9 so that 65 the ring 14 may be pressed tightly against the gasket. Preferably, a number of clamping screws 15 are used for clamping the ring 14 against the ring 9 and thereby providing a tight joint which may be readily opened 70 up whenever desired. The ring 9 is formed with a depending flange 16 having an annular notch 17 in which the upper edge of the inner casing 8 is fitted and to which it is secured, preferably by a line of solder 18 75 whereby a smooth and uninterrupted surface is provided from the upper edge of the ring 14 to the bottom of the inner casing 8. This will prevent any leakage of cooling means arranged in the space 19 while at 80 the same time permitting containers for ice cream or other material to be readily inserted into the various receptacles 2 without injury to said receptacles or the inserted 85 containers.

90 In the manufacture of ice cream and similar articles, the ice cream is prepared and frozen in a container by many well known methods now in common use and after freezing is placed in the receptacles 2 for storage 95 until the same has been sold. The storage of prepared and frozen ice cream is an old and well known method of doing business but much difficulty has been produced from the present storage devices now in use.

100 By arranging the parts as shown in Figure 3, not only may the cans containing the ice cream be readily inserted and removed without injury to the cans or to the receptacles 2 but the ice cream may be kept 105 properly cooled.

What I claim is:—

1. In an apparatus for storing ice cream, a receptacle comprising an outer casing, an inner casing spaced from the outer casing, 110 a ring having an annular recess positioned so that the upper part of the outer casing

- will fit in said annular recess, a second ring having an interior annular recess positioned so that the upper part of the inner casing will fit therein, securing means for securing 5 said rings to the respective casings, said second mentioned ring having a flange projecting within the first mentioned ring and means for rigidly clamping said rings together.
- 10 2. In an ice cream storage apparatus, a receptacle comprising an outer casing, an inner casing spaced therefrom, a ring secured to said outer casing and having an inwardly extending flange, a second ring 15 fitting flatwise against said flange and provided with an inwardly extending flange projecting within the first mentioned ring, the flange of the second mentioned ring being rigidly secured to said inner casing and clamping screws for clamping said 20 rings rigidly together.

CARL A. KULENKAMPFF.
